Patented Mar. 9, 1920.

Inventor:
John D. Pedersen,

By his Atty, J. W. Richards.

UNITED STATES PATENT OFFICE.

JOHN D. PEDERSEN, OF JACKSON, WYOMING.

FIREARM.

1,333,572.

Specification of Letters Patent. Patented Mar. 9, 1920.

Application filed April 22, 1918, Serial No. 230,042. Renewed May 29, 1919. Serial No. 300,791.

To all whom it may concern:

Be it known that I, JOHN D. PEDERSEN, a citizen of the United States, residing in Jackson, in the county of Lincoln and State of Wyoming, have invented certain new and useful Improvements in Firearms, of which the following is a specification.

This invention relates to that class of firearms in which the barrel is without longitudinal movement relative to the frame, but is detachably united thereto.

My present improvements are especially applicable to that class of small-arms commonly designated as auto-loading pistols; these usually comprise three principal members, a frame, a bolt-carrier (or "breech-slide") slidably mounted on the frame, and a non-reciprocating barrel slidably supported at its forward end in the bolt-carrying slide, and at its rear end detachably connected to the frame.

The present invention is in part in the nature of an improvement on the mechanism described and claimed in my copending application, Serial No. 209,485, filed Dec. 29, 1917, to which reference may be had; also, I employ in the mechanism herein illustrated, certain features described and claimed in my copending application, Serial No. 204,149, filed November 27th, 1917, including the improved interlock-connection therein described for detachably uniting the barrel to the frame and comprising a transverse bar, or "cross-bar", that is directly connected with the breech-slide for holding in place and releasing such cross-bar.

In the accompanying drawing forming a part of this specification, Figure 1 is a side view or elevation of the upper portion of an auto-loading pistol comprising my present improvements in a preferred form and arrangement thereof; in this view the "bolt-carrier", or breech-slide, S, is shown in its forward or firing position.

Fig. 2 is a side elevation similar to and drawn in alinement with and below Fig. 1, but showing the breech-slide S retracted on the frame, F, to about the usual loading position.

Fig. 3 is a longitudinal section for illustrating the arrangement of the shaft-form

cross-bar, C, whereby the barrel, B, and frame, F, are detachably united.

Fig. 4 is a partial plan view drawn on an enlarged scale and with some portions broken away or shown in section, for illustrating the preferred arrangement of the principal coacting members.

Fig. 5 is a cross-sectional view taken about in line X⁵, Fig. 3, for illustrating said barrel-and-frame-uniting cross-bar, C, in a side view thereof; this view is drawn on a scale corresponding to Fig. 4.

The detail views Figs. 6, 7, and 8, are respectively, a plan view, side view and an end view of the rotatable cross-bar, or shaft, C, in the preferred form thereof shown in Figs. 1 to 5, inclusive.

The detail views Figs. 9, 10, and 11, are respectively, a plan view, (as in Fig. 4), a side view, (as in Figs. 1, 2), and an end view, (as seen from the left-hand in Figs. 1, 2, 4), of the slide-lock member, or lever, d.

Figs. 12 and 13 are fragmentary side views, (corresponding to a mid-portion of Fig. 1), for illustrating certain features of the operation of the mechanism, as herein-after more fully explained.

Fig. 14 is a sectional plan view, similar to a portion of Fig. 4, for illustrating a modification as regards the manner of supporting the slide-lock member; and, Fig. 15 is a fragmentary side view drawn below and in alinement with Fig. 14, for further illustrating said modification.

Similar characters designate like parts in all the views.

In the drawing, F represents the upper portion of the frame or "receiver" of an auto-loading pistol of the class to which my present invention is applicable. This frame-member in practice, may be made of any suitable design and proportions, and the particular design, F, shown herein, has been selected merely for the purposes of illustration, and because it may be considered as typical of various other such frames which are already well-known in this art.

The bolt-carrying breech-slide,—designated in a general way by S,—is provided with a lock-face and is shown slidably mounted for reciprocatory movements forwardly and

rearwardly on the frame F in a well-known manner, and is thus retractable through a loading stroke from a firing to a loading position. The slide F may be guided in its 5 said movements by means of the usual kind of interengaging ribs and grooves; these are clearly shown (in one suitable form thereof) in the sectional view Fig. 5, and being already common in the art, do not 10 require a particular description.

The forward portion of the slide S, (at the left-hand in Figs. 1 and 2) is shown formed with an interior barrel chamber, 3^a, and as having in section, (Fig. 5), a customary inverted U-shape, so that the slide, at the section indicated, may be said to have,—to be made up of,—a top-wall, as 3^b, (usually curved about as shown), and the two depending side-walls, 3^c, 3^{c'}, which may usually 15 extend downwardly,—about as herein shown,—to a position somewhat lower than the bore of the barrel. In one of these side-walls,—in this instance, the slide-wall 3^c—there is formed a recess or gate-way, 20 as 2. Thus, it may be said that the slide, S, has a depending side-wall having an inwardly-facing surface thereof in a position for being,—on a partial retraction of the slide,—drawn out of engagement with the 25 cross-shaft and the slide-lock, to thereby first permit the cross-shaft, and later the slide-lock to be withdrawn. For these purposes, as also set forth in my said prior 30 applications, said depending wall, as 3^c engages over one side of the frame, and the cross-shaft seats are positioned in the frame at a height partly above and partly below 35 the lower edge of said depending wall.

The barrel is designated in a general way 40 by B, and is shown inclosed within the slide-chamber 3^a, (Figs. 3, 4), excepting that the forward end, 2^a, is shown slidably supported in a well-known manner in a ring or bearing, 3^d, which is removably fixed in the forward end of said slide member, so that said 45 end-portion 2^a may be said to extend outwardly, in a forward direction, from said chamber, 3^a; this feature of the barrel-mounting is also illustrated in my aforesaid 50 prior applications. The temporary removal of said ring 3^d, also facilitates the preliminary assembling of the slide and barrel, as will be readily understood. The rear end, 2^b, of the barrel B is shown enlarged to 55 nearly fill, transversely, said chamber 3^a, and thus also to form at 2^c, a shoulder, between which and said bearing 3^d, the slide-actuating spring, N, is held under suitable compression.

60 In the system as thus far described, of organizing the three principal members of an auto-loading pistol, it is contemplated that,—for the purposes of my present improvements,—the barrel at the rearward end 65 thereof will be supported and releasably re-

tained in position by an interlock-connection directly with the frame. It is also desirable, obviously, thus releasably to unite the barrel and frame in such a manner that the rearward end of the barrel can have no material 70 amount of movement,—can have no “play,” properly so called,—transversely of the frame either laterally or vertically. When the slide S has the usual upper wall, (as indicated for instance, at 3^b, Fig. 3), of 75 course, the barrel B will be covered or “housed” in by said slide-wall. However, the rear end 2^b of the barrel, is preferably so reduced in size relative to said chamber space within the slide, as not to actually 80 bear against the inner surface of said slide-wall,—thus avoiding the possibility of any undue friction as between the barrel and the moving slide. When said parts are thus arranged and properly fitted, a slight space 85 will be formed between the slide-walls and barrel-end 2^b, as indicated at 3^e, (Figs. 3 and 5), where,—in accordance with a conventional practice,—the very small amount of space actually or normally required is 90 shown somewhat enlarged to secure clearness of illustration.

For releasably connecting the barrel with the frame, these members are herein shown as being provided with interengaging portions of the nature of an interlock device. Accordingly, as a suitable form thereof, the frame F is herein shown having formed therein the recess α^a , (see Figs. 3, 5), and the barrel B is shown provided with a 100 downward extension which in practice may have any convenient form suitable for the particular size and shape of said recess. Said depending portion of the barrel, should, of course, fit rather closely between the side 105 walls of the recess so that the rearward end of the barrel will be held in place with a proper degree of rigidity.

When the barrel is put in place on the frame, these two members are then strongly 110 united by means of a transverse bar, as C, which, for the present purposes is made circular in section, so that it may be turned in and fitted to be turned in, said alined seats, and which, being seated in the frame and passing through the barrel, is thereby adapted for directly taking the recoil force of the barrel after the manner of a beam which is supported at each end thereof and has a heavy pressure applied mid-way of its length and 115 in a direction transverse thereto. Also, it may be said that the usual slide advancing spring, N, is a slide-actuating means coactive with, and appurtenant to, the assembled 120 frame, barrel and slide, for subjecting the 125 slide to a forward thrust.

cross-shaft to a resistance to being turned in said shaft-seats, and for transmitting a movement-resisting force through said shaft, C, (and, in this instance, through the actuator device 7 thereof) to the slide-lock.

The cross-shaft C is herein shown provided with an enlarged end, or head-portion, as c^4 , which is reduced at c^2 to form the transverse stop-face c^6 , and is shown so fitted 10 that the face c^7 thereof (Fig. 4) comes against a side surface of the barrel lug b' , and is thereby held against longitudinal movement in one direction. Outward movement is similarly prevented by said transverse surface c^6 of said shaft-head c^4 engaging the inner surface 3^b of the slide wall 3^c ,—see Fig. 4. When the cross-shaft is thus provided with the two movement-limiting surfaces, as c^6 and c^7 , the opposite end, c^5 of 15 said shaft may be so arranged and fitted as not to actually engage with or against the slide-wall 3^c ; this is a preferred arrangement and is the one shown in the drawing.

On account of the usual mode of taking 20 the pistol in hand, it will usually be desirable to locate the cross-shaft with the head c^4 thereof at the left-hand side of the pistol frame, and this, it will be understood, is the arrangement herein illustrated. However, 25 it will be evident that said arrangement may be reversed, should occasion require, and the firearm be constructed in such a manner (not herein shown) as to bring said cross-bar or shaft with the head thereof at 30 the right-hand side of the frame.

In order to provide for inserting and 35 withdrawing said cross-shaft C when constructed and positioned as here explained, one of the slide-walls, (in this instance, the wall 3^c) has a recess, or shaft-releasing space, as 2, (Figs. 1, 2, 12, 13), in such a position therein that when the slide is at some convenient point between the ends of its travel, or working stroke from a firing to a 40 loading position, this recess or space will come into alignment with said cross-shaft seat a^4 , of the frame (Fig. 12) and thereby permit said shaft to be pushed out through said recess as through a door or gate-way 45 therefor.

In practice, said recess or gate-way, 2, should be so located as not to be in front of the face or shoulder c^6 , of the cross-shaft when the slide S is being held in a fully retracted position (Fig. 2), and so that the user, when desiring to take out the cross-shaft, will be required to draw back the slide for only a short distance. This arrangement,—as indicated by comparison of 50 Figs. 1, 2, 12, 13,—also has the advantage that in the normal operation of the firearm, said gate-way recess will pass the cross-shaft C while moving at a high velocity, thereby safeguarding the operation. A further safe- 55 guard is also secured, since the force of the

spring N, and the action of the recoil, each applies pressure to the cross-shaft C during the time the recess 2 is passing this shaft, and thus tends to hold the shaft so firmly as to prevent any longitudinal movement 70 thereof during such a brief time-interval.

In my aforesaid application Serial No. 209,485, I have shown and described how a stop-arm, (also designated as the slide-lock), may be carried directly upon a frame-and-shaft-connecting cross-bar which operates as an arm-carrying shaft, and which, also, is subjected to a resistance derived from the force of the slide-actuating spring transmitted through the barrel; in that construction the stop-arm axis and the cross-shaft axis, are coincident. In my present improvements, a different organization has been employed, in which the slide-lock arm, or lever, d , is formed as a separate member 75 and is operably-supported on the frame independently of the cross-shaft C. The slide-lock is herein shown operatively connected with said shaft C by a shaft-turning actuator device appurtenant to said lever or arm; 80 in this instance, said device is the tooth or projection 7, which coactively engages the shaft. For these purposes, said member d is shown provided with a hub or journal, d^4 , which is located adjacent to said shaft-head 85 c^4 . Thus the arm axis, as i' , (Fig. 4), is located rearward of the shaft axis i , and accordingly said arm, d , may be relatively shorter than indicated in said construction 90 as shown in Figs. 1 to 4 of said prior application, No. 209,485, provided of course, that the cross-shaft and the inwardly-projecting projection d^2 are in the same positions relatively to the frame and to each other.

Thus the present arrangements, by providing for the shorter stop-arm, have the advantage of providing for a swinging movement of said arm through a relatively wide angle, so that the operator can more clearly distinguish the position and feel the action 105 of the stop-arm when this is swung upward or downward under said resistance to engage with and disengage from said lock-face, 3^k , of the slide S. This relatively large rotative or turning movement, or stroke of 110 said arm d , also rotates or turns the cross-shaft C, through a correspondingly large arc of movement, and thus provides a better frictional resistance than would otherwise be secured from said transmitted force of 115 the slide-actuating spring.

The locking-arm d is preferably supported on the frame by means of a pivotal connection therewith, this connection being located adjacent to and rearward of shaft C. 120 For this purpose the short hub-portion c^4 of the stop-arm may be so formed as to constitute a journal and be closely fitted to rotate or turn within the bearing at b^5 , formed in the main frame F; and, by a precise locating 125 130

of this bearing, the forward face at d^9 of the arm may bear against the rearward side of the shaft at c^9 , (as indicated in Figs. 4 and 12), so that a support will thus be provided in a position tending to prevent any undue outward movement, or play, of the rearward end of the stop-arm. This feature of the rolling engagement of the said two portions c^4 and d^4 is deemed to be especially 10 desirable, whenever the hub d^4 shall be fitted to turn rather freely, so that it might have an excess of freedom or play, in its said bearing.

Instead of the construction just described, 15 however, said hub d^4 in some instances may be made tubular, as shown for instance in Figs. 14 and 15. In this modification, a stud or fixed shaft, b' , is supported in (or it may be formed on) the frame, in any well-known or suitable manner, so that the arm d will turn upon this shaft, as upon a pivot. This arrangement is deemed to be preferable when it is desired, for any reason, to have a clear space, as t , (Fig. 14), between the stop-arm 25 and the surface of shaft C; the provision of this space t , of course, requires that the tooth 7 shall project from the hub d^4 a relatively greater distance than otherwise, in order to properly engage with the 30 shaft C.

Said lever or arm d , as will now be evident, constitutes a means, or "handle" whereby the operator may turn the shaft C under the transmitted pressure of said slide-actuating spring during a swinging movement of the slide-lock about the pivoted connection thereof with the frame, and whereby the slide S may be locked in and released from its retracted position. Similarly as described in my said application Serial No. 209,485, the lever d is herein shown provided with a slide-lock face, 4^e , and with the inward projection, d^2 , whereby this slide-lock member d may be actuated 45 upwardly toward the slide-engaging position thereof, by means of the usual spring-actuated magazine follower, as n , (Figs. 3, 4), and thereby lock the slide S in retracted position (Fig. 2) whenever the supply of 50 cartridges in the magazine shall become exhausted.

This arrangement will be clearly understood from the sectional plan view Fig. 4, in which said lever arm d , is shown provided 55 with inward projections d^2 extending through the opening at f^3 of the frame. In this view the inner end of said projection d^2 is shown in position for engaging with the upper side of the usual follower as n , of 60 the ordinary magazine, m , of the firearm. (See Figs. 3, 4, 14.) Since said follower n is in practice actuated by a spring (which, being a well-known device, is not shown), when said follower rises upwardly to a 65 point for engaging said inward projection

d^2 , thereby the lever-arm d will be spring-actuated, for the purpose of raising the lock-end or face 4^e of said lever-arm into contact with the lower side of the slide S, (Fig. 15), so that when the slide is drawn rearwardly 70 to the position indicated in the side view Fig. 2, said face 4^e of the lever-arm will engage the rearward face 3^e of the recess 2, and thus operate in a well-known manner as a slide-stop, or lock, for holding the slide 75 in said retracted position.

One feature of my present improvements relates to the means whereby a frictional resistance or restraint is transmitted to, and applied to, the slide-lock, or stop-arm, d , 80 by transmitting thereto a resistant force derived from the aforesaid slide-actuating spring. This spring, as N , acting through the barrel B and its depending part, or lug, b' , applies a pressure to the cross-shaft C, 85 and thereby tends to restrict the freedom of rotation, or turning movement, of this shaft by the amount of the friction so produced. The stop-arm d and said shaft C being separate members, and neither one comprising 90 the other, are therefore to be provided with some suitable coacting action means whereby these two members may have concurrent rotative movements about their respective axes; the extent of these movements, of 95 course, will be determined, in practice, by the required extent, in any particular instance, of the swinging movement of the stop-arm d .

A preferred means for accomplishing 100 these objects, is illustrated herein, and consists of a one-tooth form of gear-segment, comprising a projecting "tooth", or actuator-member, as 7, projecting from the hub-portion d^4 of said arm, and engaging in a 105 coactive manner with said shaft C, which shaft, for such purpose, may have a suitable tooth-receiving space, as 8, (see Figs. 6 to 11), into which said tooth meshes, after the manner, substantially, of ordinary 110 toothed-gearing. Thus when the stop-arm is forcibly turned, or swung up or down, the shaft C will be rotated in the reverse direction and by an amount corresponding to the radius-ratio of the respective coacting gear-tooth, or actuation faces. Also, when placed in either said position, up or down, the control thus supplied through the shaft C, constantly tends to hold the lock-arm d in such position until it shall again 115 be forcibly shifted. Thus the slide-lock may be said to have appurtenant thereto a shaft-turning actuator, which may be in the form of a tooth-device, as 7, and is in position and connected for turning the shaft C in 120 said shaft-seats of the barrel and frame, and this coaction may be said to be such as to impart concurrent turning movements to 125 said members C and d , in opposite directions, respectively.

The tooth-space 8, is shown formed in the larger portion c^4 of the cross-shaft C, so that said space does not need to extend nearer to the shaft-axis line i , (Fig. 4), than 5 is the outer surface of the smaller portion c^5 of this shaft. By means, of this arrangement, one end of said space 8 is open, or unclosed, whereas the other end is closed by the transverse surface, or face, 8^a , (Fig. 7), 10 which,—in the assembled mechanism,—engages against the outer-end face 7^a of the actuator device, or tooth 7, as will be seen by a comparison of the several views in which these faces and other details are illustrated. Thus said tooth-space end-face 8^a 15 constitutes a stop-face whereby to engage the outer-end face 7^a of the tooth 7 and thereby operate as a means, whereby to retain the arm-hub d^4 (and the slide-lock as 20 a whole) securely in place.

This result, of course, requires that the shaft C shall itself, in the assembled mechanism, be held against retraction (longitudinally thereof) out of the frame; this 25 shaft-retention is herein obtained by making on said enlarged portion c^4 , the transverse face c^6 in position for engaging with the inner slide-wall face 3^b , (Figs. 5, 15), in the manner already explained. Thus 30 said slide-wall normally,—and excepting during the operation of disassembling,—is a means appurtenant to the slide S for holding the shaft C in place, while the shaft similarly retains in proper position, the 35 stop-arm hub c^4 by the described coaction of the faces 8 and 7^a . Said tooth device, as 40 7, constitutes one means (herein shown as being appurtenant to the slide-lock), which is in position and connected for turning 45 said shaft during the swinging movement of the lever-form slide-lock in a direction to engage said stop-arm with said lock-face of the slide; said shaft, during such movement, is turned under the transmitted pressure of said slide-actuating spring, which 50 is thus one means appurtenant to the assembled frame, barrel and slide, for subjecting the cross-shaft to a frictional resistance to being turned in the aforesaid alined shaft seats.

When the mechanism is thus organized and fully assembled, an important advantage is secured in that the stop-lever d will be positively held in place at all times, 55 whether the slide S shall be moving, or whether this slide shall be at rest at any point whatever within the length of its stroke. To disassemble the mechanism, said slide S is moved to a partially retracted 60 position (Fig. 12), for bringing the locking recess 2 directly over the enlarged end, c^4 , of the assembling shaft C; at this time the slide-wall 3^c stands directly in front of the face d^b of the stop-lever hub d^4 , thereby retaining said lever d securely in place and in

a positive manner. Said slide having been thus positioned, the operator may then push on the smaller end c^5 of said shaft C, (pushing toward the right-hand in Fig. 5), and thus entirely withdraw this member from 70 its seat in the frame. After such removal of said cross-shaft or cross-bar, (Fig. 13), and while said stop-lever remains in place, the operator is then free to draw the slide and barrel off from the frame in a forward direction; and, during this disassembling operation, the inward projection d^2 of the stop-lever d will continue to stand with the inner end, or point thereof (Fig. 4) engaging above the magazine follower n . 80

After the cross-shaft has been removed, (in such or similar manner as just explained), the operator may then, if desired, move the main slide S to the position (Fig. 13) for bringing said recess 2 above the hub 85 d^4 of the stop-lever, and may then draw this lever directly away from the frame, (downwardly in Figs. 4, 14), since the stop-face portion of said lever-hub (the part directly back of face d^b) will then pass freely 90 through said recess. However, if slide S should be placed in said position, (as in Fig. 13), before the cross-shaft C had been removed, then the slide-wall 3^c engages forward of the stop-face c^6 , and thereby the 95 slide continues by a direct action to hold said cross-shaft securely in place; at the same time the inwardly-facing face 8^a ,—at the forward end of the tooth-space 8,—engages forward of the outer end of the stop-lever tooth-device 7, and thus prevents the withdrawal 100 of the hub-portion d^4 of said lever.

From the foregoing description as illustrated, it will now be evident that by reason of the organization here described, said 105 cross-shaft and stop-lever members are co-actively engaged, and are made removable one only at a time, and only in the sequence described. Also, as will now be evident, the stop-lever d is not provided with the cross-shaft, nor does this shaft, as C, have any handle or like device appurtenant thereto, or whereby to aid in the removal thereof from the frame. On the contrary, after the cross-shaft shall be withdrawn, the frame, 110 slide and barrel may be disassembled while said lever d remains assembled on the frame, so that said stop-lever is in no way involved in the operation of removing the cross-shaft. The described form of shaft-actuator, and 115 the manner of its said engagement, constitutes said actuator a means appurtenant to the slide-lock whereby this member is normally held in place, and is only permitted to be withdrawn subsequent to, and not in advance of the withdrawal of the cross-shaft. 120

Having thus described my invention, I claim—

1. In a firearm, in combination, a frame and a barrel each provided with interlock 130

- portions having transversely-disposed there-
in alined cross-shaft seats, of a slide having
a lock-face and supported for reciprocating
movements forwardly and rearwardly on the
frame; a barrel and frame uniting cross-
shaft disposed in and fitted to be turned in
said alined seats and in position for directly
uniting the frame and barrel without inter-
vening parts; a slide-lock operably sup-
ported on the frame for working movements
to engage with and disengage from said
lock-face; and, actuating means operatively
connecting the cross-shaft and slide-lock for
concurrent movements.

5 2. In a firearm, in combination, a frame
and a barrel each provided with interlock
portions having transversely-disposed there-
in alined cross-shaft seats, of a slide having
a lock-face and supported for reciprocating
movements forwardly and rearwardly on the
frame; a barrel and frame uniting cross-
shaft disposed in and fitted to be turned in
said alined seats, and in position for directly
uniting the frame and barrel without inter-
vening parts; a lever-form slide-lock op-
erably supported on the frame for swinging
working movements to engage with and dis-
engage from said lock-face; and, a shaft-
turning actuator in position and connected
25 for turning the cross-shaft from the swing-
ing movement of the slide-lock.

30 3. In a firearm, in combination, a frame
and a barrel each provided with interlock
portions having transversely-disposed there-
in alined cross-shaft seats, of a slide having
a lock-face and supported for reciprocating
movements forwardly and rearwardly on the
frame; a barrel and frame uniting cross-
shaft disposed in and fitted to be turned in
said alined seats and in position for directly
uniting the frame and barrel without inter-
vening parts; a slide-lock operably sup-
ported on the frame for working movements
35 to engage with and disengage from said
lock-face, and also supported in a position
adjacent to said shaft; and, a shaft-turning
actuator appurtenant to the slide-lock and
in position and connected for turning the
cross-shaft from the working movements of
40 the slide lock.

45 4. In a firearm, in combination, a frame
and a barrel each provided with interlock
portions having therein alined cross-shaft
seats, of a slide having a lock-face and
supported for reciprocating movements for-
wardly and rearwardly on the frame; a bar-
50 rel and frame uniting cross-shaft disposed
in and fitted to be turned in said alined
seats, and in position for directly uniting
the frame and barrel without intervening
parts; means appurtenant to the assembled
frame, barrel and slide for subjecting the
cross-shaft to a frictional resistance to being
turned in said shaft-seats; a slide-lock op-
erably supported on the frame for working
movements to engage with and disengage
55 from said lock-face; and, actuating means
operably connecting the cross-shaft and
slide-lock for concurrent movements.

60 5. In a firearm, in combination, a frame
and a barrel each provided with interlock
portions having transversely-disposed there-
in alined cross-shaft seats, of a slide having
a lock-face and supported for reciprocating
movements forwardly and rearwardly on the
frame; a barrel and frame uniting cross-shaft disposed in and fitted to be turned in said alined seats and in position for directly uniting the frame and barrel without intervening parts; means appurtenant to the assembled frame, barrel and slide for subjecting the cross-shaft to a frictional resistance to being turned in said shaft-seats; a slide-lock operably supported on the frame for working movements to engage with and disengage from said lock-face; and, actuating means operatively connecting the cross-shaft and slide-lock for concurrent movements.

65 6. In a firearm, in combination, a frame
and a barrel each provided with interlock
portions having transversely-disposed there-
in alined cross-shaft seats, of a slide having
a lock-face and supported for reciprocating
movements forwardly and rearwardly on the
frame; a barrel and frame uniting cross-shaft disposed in and fitted to be turned in said alined seats; means appurtenant to the assembled frame, barrel and slide for subjecting the cross-shaft to a frictional resistance to being turned in said shaft-seats; a lever-form slide-lock pivotally supported on the frame for turning movements to engage with and disengage from said lock-face; and, actuating means operatively connecting the cross-shaft and slide-lock for concurrent turning movements in opposite directions, respectively.

7. In a firearm, in combination, a frame
and a barrel each provided with interlock
portions having transversely-disposed there-
in alined cross-shaft seats, of a slide having
a lock-face and supported for reciprocating
movements forwardly and rearwardly on the
frame; a barrel and frame uniting cross-
shaft disposed in and fitted to be turned in
said alined seats; a slide actuating spring
intermediate to the slide and barrel, and in
position and connected for subjecting the
cross-shaft to a frictional resistance against
turning in said shaft-seats; a slide-lock op-
erably supported on the frame for working
movements to engage with and disengage
from said lock-face; and, actuating means
operably connecting the cross-shaft and
slide-lock for concurrent movements.

8. In a firearm, in combination, a frame
and a barrel each provided with interlock
portions having transversely-disposed there-
in alined cross-shaft seats, of a slide having

a lock-face and supported for reciprocating movements forwardly and rearwardly on the frame; a barrel and frame uniting cross-shaft disposed in and fitted to be turned in said alined seats; a slide actuating spring intermediate to the slide and barrel, and in position and connected for subjecting the cross-shaft to a frictional resistance against turning in said shaft-seats; a lever-form 10 slide-lock pivotally supported on the frame for turning movements to engage with and disengage from said lock-face; and, actuating means operably connecting the cross-shaft and slide-lock for concurrent turning 15 movements in opposite directions, respectively.

9. In a firearm, in combination, a frame and a barrel each provided with interlock portions having transversely-disposed there-in alined cross-shaft seats, of a slide having a lock-face and supported for reciprocating movements forwardly and rearwardly on the frame; a barrel and frame uniting cross-shaft disposed in and fitted to be turned in 20 said alined seats; a slide actuating spring intermediate to the slide and barrel, and in position and connected for subjecting the cross-shaft to a frictional resistance against turning in said shaft-seats; a slide-lock operably supported on the frame for working movements to engage with and disengage from said lock-face; and, a shaft-turning actuator appurtenant to the slide-lock and in position and connected for turning the cross-shaft 25 on the working movement of the slide-lock.

10. In a firearm, the combination with a frame and with a barrel, each provided near the rearward end of the barrel with interlock portions having transversely-disposed and alined cross-shaft seats, of a slide having a lock-face and supported for reciprocating movements on the frame; a slide-actuating spring intermediate to the slide and barrel; a barrel and frame uniting cross-shaft disposed and fitted to be turned in 45 said alined seats while subjected to friction derived from said spring; a slide-lock supported for a swinging movement on the frame and having a pivotal connection with the frame; and, a shaft-turning actuator appurtenant to said slide-lock and in position and connected for turning the shaft under the transmitted pressure of said slide-actuating spring during a swinging movement of the slide-lock about said pivotal connection for coaction with said lock-face.

11. In a firearm, the combination with a frame and with a barrel, each provided near the rearward end of the barrel with interlock portions having transversely-disposed and alined cross-shaft seats, of a slide having a lock-face and supported for reciprocating movements on the frame, a slide-actuating spring intermediate to the slide and

barrel; a barrel and frame uniting cross-shaft disposed and fitted to be turned in said alined seats while subjected to friction derived from said spring; a slide-lock supported for a swinging movement on the frame and having a pivotal connection with the frame in a position contiguous to said shaft; and, a shaft-turning actuator appurtenant to and having a fixed position on said slide-lock, and in position and connected for turning the shaft under the transmitted pressure of said slide-actuating spring during a swinging movement of the slide-lock about said pivotal connection for coaction with said lock-face.

12. In a firearm, the combination with a frame and a barrel each provided near the rearward end of the barrel with interlock portions having transversely disposed and alined cross-shaft seats, of a slide having a lock-face and retractably supported on the frame; a barrel and frame uniting cross-shaft disposed and fitted to be turned in said alined seats and in position for directly uniting the frame and barrel without intervening parts; a slide-lock supported on the frame by a pivotal connection adjacent to and rearward of said shaft, and having a stop-face in position for being swung into engagement with said lock-face when the slide is retracted; and, a shaft-turning actuator appurtenant to the slide-lock and connected for turning said shaft in said alined shaft-seats of the frame and the barrel, whereby the force of the recoil applies a pressure to the shaft for thereby frictionally restraining the movements of said shaft and also of said slide-lock.

13. In a firearm, the combination with a frame and a barrel each provided near the rearward end of the barrel with interlock portions having transversely disposed and alined cross-shaft seats, of a slide having a lock-face and retractably supported on the frame; a barrel and frame uniting cross-shaft disposed and fitted to be turned in said alined seats and in position for directly uniting the frame and barrel without intervening parts, a slide-lock supported on the frame by a pivotal connection adjacent to and rearward of said shaft, and having a stop-face in position for being swung into engagement with said lock-face when the slide is retracted; a shaft-turning actuator appurtenant to the slide-lock and connected for turning said shaft in said alined shaft-seats of the frame and the barrel, whereby the force of the recoil applies a pressure to the shaft for thereby frictionally restraining the movements of said shaft and also of said slide-lock; and, means appurtenant to the slide for normally holding in place said cross-shaft and slide-lock.

14. In a firearm, the combination with a frame and a barrel each provided near the

- rearward end of the barrel with interlock portions having transversely-disposed and alined cross-shaft seats, of a slide having a lock-face and retractably supported on the frame; a barrel and frame uniting cross-shaft disposed and fitted to be turned in said alined seats; a slide-lock supported on the frame by a pivotal connection adjacent to and rearward of said shaft, and having a stop-face in position for being swung into engagement with said lock-face when the slide is retracted; a shaft-turning actuator appurtenant to the slide-lock and connected for turning said shaft in said alined shaft-seats of the frame and the barrel, whereby the force of the recoil applies a pressure to the shaft for thereby frictionally restraining the movements of said shaft and also of said slide-lock; and, means appurtenant to the slide for normally holding in place said cross-shaft and slide-lock, and comprising a recess arranged for permitting the withdrawal thereof one only at a time.

15. In a firearm, the combination with a frame and with a barrel, of a slide having a lock-face and retractably supported on the frame, said frame and barrel having near the rearward end of the barrel, interlock portions provided transversely with a cross-shaft seat; a barrel and frame uniting cross-shaft disposed in said shaft-seat, and in position for directly uniting the frame and barrel without intervening parts; a slide-lock consisting of a member formed separately from said cross-shaft, and operably supported on the frame adjacent to said cross-shaft, and in position for engaging with and disengaging from said lock-face when the slide is retracted; and, means coactive between the slide-lock and cross-shaft for turning the cross-shaft from the operation of the slide-lock when the slide is in a retracted position.

25. 16. In a firearm, the combination with a frame and with a barrel, of a slide having a lock-face and retractably supported on the frame, said frame and barrel having near the rearward end of the barrel, interlock portions provided transversely with a cross-shaft seat; a barrel and frame uniting cross-shaft disposed in said shaft-seat and in position for directly uniting the frame and barrel without intervening parts, and also having a transverse bearing face in a position adjoining one side of the frame; a slide-lock consisting of a member formed separately from said cross-shaft, and operably supported on the frame adjacent to said cross-shaft; and in position for engaging with and disengaging from said lock-face when the slide is retracted; means coactive between the slide-lock and cross-shaft for operating the cross-shaft from the operation of the slide-lock when the slide is in a retracted position; and, means appurtenant to the slide and in position for coaction with said transverse bearing face of the cross-shaft when the slide is retracted to a position for a slide-lock to engage said lock-face.

30. 17. In a firearm, the combination with a frame and with a barrel, of a slide having a lock-face and retractably supported on the frame, said frame and barrel having near the rearward end of the barrel, interlock portions provided transversely with a cross-shaft seat; a barrel and frame uniting cross-shaft disposed in said shaft-seat, and also having a transverse bearing face in a position adjoining one side of the frame; means appurtenant to the slide and in position and arranged for coaction with said transverse bearing face of the cross-shaft and thereby hold the cross-shaft from displacement during one portion of the retractive movement of the slide, and for withdrawing from such coaction in one position of the slide; a slide-lock consisting of a member formed separately from said cross-shaft, and operably supported on the frame adjacent to said cross-shaft, and in position for engaging with and disengaging from said lock-face of the slide; and, means coactive between the slide-lock and cross-shaft for turning the cross-shaft from the operation of the slide-lock.

35. 18. In a firearm, the combination with a frame, and with a barrel, of a slide having a slide-lock-engaging lock-face and retractably supported on the frame, said frame and barrel having interlock portions provided transversely with a cross-shaft seat, and said slide having a side-wall with an inner surface in position for engaging with and thereby normally retaining in place a cross-shaft and a slide-lock; a barrel and frame uniting cross-shaft disposed in said shaft seats and provided with an outwardly-facing and transverse face in position thereon for engaging said inner surface of the slide, and also provided longitudinally thereof with an actuator receiving space having at its outer end a transverse and inwardly-facing slide-lock-retaining face; a slide-actuating spring in position and connected for applying pressure to the cross-shaft and thereby frictionally restraining the turning of this shaft during the rearward movement of the slide on the frame; a slide-lock having a slide-engaging face and journaled on the frame adjacent to said cross-shaft, and provided with a shaft-turning actuator in position for engaging in said actuator-receiving space and against said slide-lock retaining face of the cross-shaft for thereby preventing a withdrawal of the slide-lock in advance of a withdrawal of the cross-shaft, and also provided with an outwardly-facing transverse face in position thereon for engaging said inner surface of the slide.

the slide-wall; and, a magazine follower in position and connected for upwardly actuating the slide-lock to engage the slide-engaging face thereof with the lock-face of the 5 slide when the slide is retracted, and also during such movement to turn the cross-shaft in said shaft-seat and under the frictional restraint due to the transmitted pressure of said slide-actuating spring, 10 said slide wall and the inner surface thereof having therein a recess which, when brought to said shaft-seat permits the withdrawal through the recess of the cross-shaft while the slide-lock is held in place by the slide, 15 and which, when brought to the slide-lock journal subsequent to such a withdrawal of the cross-shaft, permits the withdrawal of the slide-lock.

19. In a firearm, the combination with 20 a frame, and with a barrel, of a slide having a slide-lock-engaging lock-face and retractably supported on the frame, said frame and barrel having interlock portions provided transversely with a cross-shaft 25 seat, and said slide having a side-wall with an inner surface in position for engaging with and thereby normally retaining in place a cross-shaft and a slide-lock; a barrel and frame uniting cross-shaft disposed 30 in said shaft seats and provided with an outwardly-facing and transverse face in position thereon for engaging said inner surface of the slide, and also provided longitudinally thereof with a tooth-receiving 35 space having at its outer end a transverse and inwardly-facing slide-lock-retaining face; a slide-actuating spring in position and connected for applying pressure to the cross-shaft and thereby frictionally restraining the turning of this shaft during 40 the rearward movement of the slide on the frame; and, a slide-lock having a slide-engaging face and journaled on the frame adjacent to said cross-shaft, and provided with 45 a shaft-turning tooth device in position for engaging in said tooth-receiving space and against said slide-lock retaining face of the cross-shaft for thereby preventing a withdrawal of the slide-lock in advance of a 50 withdrawal of the cross-shaft and also provided with an outwardly-facing transverse face in position thereon for engaging said inner surface of the slide-wall.

20. In a firearm, the combination with a 55 frame, and with a barrel, of a slide having a slide-lock-engaging lock-face and retractably supported on the frame, said frame and barrel having interlock portions provided transversely with a cross-shaft seat, 60 and said slide having a side-wall with an inner surface in position for engaging with and thereby normally retaining in place a cross-shaft and a slide-lock; a cross-shaft disposed in said shaft seats and provided 65 with an outwardly-facing and transverse

face in position thereon for engaging said inner surface of the slide, and also provided longitudinally thereof with an actuator-receiving space having at its outer end a transverse and inwardly-facing slide-lock-retaining face; a slide-lock having a slide-engaging face and journaled on the frame adjacent to said cross-shaft, and provided with a shaft-turning actuator in position for engaging in said actuator-receiving 70 space and against said slide-lock retaining face of the cross-shaft for thereby preventing a withdrawal of the slide-lock in advance of a withdrawal of the cross-shaft and also provided with an outwardly-facing 75 transverse face in position thereon for engaging said inner surface of the slide-wall; and, a magazine follower in position and connected for actuating the slide-lock in a direction to engage the slide-engaging face 80 thereof with the lock-face of the slide when the slide is retracted, and also during such movement to turn the cross-shaft in said shaft-seat, said slide-wall and the inner surface thereof having therein a recess which, 85 when brought to said shaft-seat permits the withdrawal through the recess of the cross-shaft.

21. In a firearm, the combination with a 90 frame, and with a barrel, of a slide having a slide-lock-engaging lock-face and retractably supported on the frame, said frame and barrel having interlock portions provided transversely with a cross-shaft seat, 95 and said slide having a side-wall with an inner surface in position for engaging with and thereby normally retaining in place a cross-shaft and a slide-lock; a cross-shaft disposed in said shaft seats and provided with an outwardly-facing and transverse 100 face in position thereon for engaging said inner surface of the slide, and also provided longitudinally thereof with an actuator-receiving space having at its outer end a transverse and inwardly-facing slide-lock-retaining face; and, a slide-lock having a slide-engaging face and journaled on the frame adjacent to said cross-shaft, 105 and provided with a shaft-turning actuator device in position for engaging in said actuator-receiving space and against said slide-lock-retaining face of the cross-shaft for thereby preventing a withdrawal of the slide-lock in advance of a withdrawal 110 of the cross-shaft, and also provided with an outwardly-facing transverse face in position thereon for engaging said inner surface of the slide-wall, said slide-wall and the inner surface thereof having therein a recess which, 115 when brought to said shaft-seat permits the withdrawal through the recess of the cross-shaft, and which, when brought to the slide-lock journal subsequent to such a withdrawal of the cross-shaft, 120 permits the withdrawal of the slide-lock. 125

130

22. In a firearm, the combination with a frame and with a barrel, of a slide reciprocatable on the frame and provided with a depending wall engaging over one side of the frame and there having an inwardly-facing surface in position for engaging a cross-shaft and a slide-lock, said frame and barrel each having near the rearward end of the barrel, interlock portions provided transversely with alined cross-shaft seats positioned in the frame at a height partly above and partly below the lower edge of said depending wall of the slide; a cross-shaft disposed in said alined seats and thereby releasably uniting the frame and barrel, and provided with a transverse face in position thereon for engaging said inwardly-facing surface of the slide wall, for normally holding the cross-shaft in place when the slide is in forward position; a shaft-actuating slide-lock operably supported on the frame in a position rearward of said cross-shaft and at a height partly above and partly below the lower edge of said depending wall of the slide, and which is provided with a face in position thereon for engaging with said inwardly-facing surface of the slide wall, for thereby normally holding the slide-lock in place; and said depending slide-wall having said inwardly-facing surface thereof in a position on the slide for being (on a partial retraction of the slide) drawn out of engagement with the cross-shaft and thereby (while the slide-lock is held in place) permit the cross-shaft to be withdrawn, and for being (on a further retraction of the slide), drawn out of engagement with the slide-lock, and thereby permit the slide-lock to be withdrawn.
23. In a firearm, the combination with a frame and with a barrel, of a slide reciprocatable on the frame and provided with a depending wall engaging over one side of the frame and there having an inwardly-facing surface in position for engaging a cross-shaft and a slide-lock, said frame and barrel each having near the rearward end of the barrel, interlock portions provided transversely with alined cross-shaft seats positioned in the frame at a height partly above and partly below the lower edge of said depending wall of the slide; a cross-shaft disposed in said alined seats and thereby releasably uniting the frame and barrel, and provided with a transverse face in position thereon for engaging said inwardly-facing surface of the slide wall, for normally holding the cross-shaft in place when the slide is in forward position; a shaft-actuating slide-lock pivotally supported on the frame by a journal-portion which is positioned in the frame adjacent to and rearward of said cross-shaft and at a height partly above and partly below the lower edge of said depending wall of the slide, and which is provided with a face in position thereon for engaging with said inwardly-facing surface of the slide wall, for thereby normally holding the slide-lock in place; and said depending slide-wall having said inwardly-facing surface thereof in a position on the slide for being (on a partial retraction of the slide) drawn out of engagement with the cross-shaft and thereby (while the slide-lock is held in place) permit the cross-shaft to be withdrawn, and for being (on a further retraction of the slide), drawn out of engagement with the slide-lock, and thereby permit the slide-lock to be withdrawn.
24. In a firearm, in combination, a frame having transversely thereof a shaft-seat and also having a magazine provided with a follower; a shaft supported in said shaft-seat and provided with a transverse face; a slide-lock consisting of a member formed separate from said shaft and operably-supported on the frame adjacent to said shaft and provided with a stop-face in position and arranged for coaction with the lock-face of a slide; a breech-slide retractable through a loading stroke from a firing to a loading position on the frame and provided with a lock-face in position for coaction with said stop-face when the slide is retracted to a loading-position, said slide being also provided longitudinally thereof with a shaft-engaging face in position for engaging with said transverse face on said shaft, and having therein a shaft-releasing space through which in one position of the slide said body portion of the shaft may be withdrawn from said shaft-seat; means appurtenant to the slide-lock and follower for actuating the stop-face toward the slide-engaging position thereof; and, means in position and connected for turning said shaft during the movement of the slide-lock.
25. In a fire-arm, in combination, a frame having transversely thereof a shaft-seat and also having a magazine provided with a follower; a shaft supported in said shaft-seat and provided with a transverse face; a slide-lock formed separate from said shaft and operably-supported on the frame adjacent to said shaft and provided with a stop-arm in position and arranged for coaction with the lock-face of a slide; a breech-slide retractable through a loading stroke from a firing to a loading position on the frame and provided with a lock-face in position for coaction with said stop-arm when the slide is retracted to a loading-position, said slide being also provided longitudinally thereof with a shaft-engaging face in position for engaging with said transverse face on said shaft, and having therein a shaft-releasing space through which in one position of the slide said body portion of the shaft may be withdrawn from said shaft-seat; a slide-actuating spring and means for transmitting therefrom a pressure to said shaft for frictionally restraining the turning of the shaft; means appurtenant to the stop-arm

and follower for actuating the stop-arm toward the slide-engaging position thereof; and, means in position and connected for turning said shaft during a movement of the slide-lock in a direction for engaging said stop-arm with said lock-face of the slide.

26. In a firearm, the combination, with a frame, a barrel and a slide having a lock-face, said frame having transversely thereof a shaft-seat comprising two alined seats of which one seat is larger than the other; of a frame-and-barrel uniting cross-shaft in said shaft-seat and having an enlarged 5 shaft-head portion fitting and rotatable within said larger shaft-seat; a slide-lock consisting of a member formed separately from said cross-shaft, and operably supported on the frame in position for coaction 10 with the lock-face when the slide is retracted from a firing to a loading position on the frame; and, a shaft-actuator device in position and connected for coaction 15 with said shaft-head for turning the shaft in said shaft-seats.

27. In a firearm, the combination, with a frame, a barrel and a slide having a lock-face, said frame having a shaft-seat comprising two alined seats of which one seat 10 is larger than the other; of a frame-and-barrel uniting cross-shaft in said shaft-seat and having an enlarged head portion fitting and rotatable within said larger shaft-seat, and having longitudinally there- 15 in an actuator-receiving space having actuation faces and which is open at the inner end and closed at the outer end; a slide-lock consisting of a member formed separately from said cross-shaft and sup- 20 ported for a working movement on the frame and in a position for coaction with said lock-face when the slide is retracted from a firing to a loading position; and, a shaft-actuator device in position on the 25 slide-lock for coaction with the faces of said actuator-receiving space of the shaft-head and thereby turn the shaft in said shaft-seats from a working movement of the slide-lock.

28. In a firearm, the combination, with a frame, a barrel and a slide having a lock-face, said frame having a shaft-seat comprising two alined seats of which one seat is larger than the other; of a frame-and-barrel uniting cross-shaft in said shaft-seat and having an enlarged head portion fitting and rotatable within said larger shaft-seat, and having longitudinally therein an actuator-receiving space having actuation faces and which is open at the inner end and is closed at the outer end by a transverse face; a slide-lock operably supported on the frame in position for coaction with said lock-face when the slide is retracted from a firing to a loading position on the frame, said slide-

lock being provided with a shaft-actuator device in position for coaction with the faces of said actuator-receiving space of the shaft-head to turn the shaft in said shaft-seats, and the shaft-head having said transverse 70 face thereof in a position for engaging outside of said actuator device and thereby retain the slide-lock in place on the frame.

29. In a firearm of the class described, the combination with a frame having transversely thereof a shaft-seat, and with a slide having a lock-face, of a cross-shaft in said shaft-seat, and a slide-lock having a hub-portion journaled in the frame adjacent to said shaft-seat, and having a stop-face co-operative with said lock-face of the slide, 75 said shaft and said hub-portion having appurtenant to one of them an actuator-device coactively engaging the other of them, and arranged for turning the shaft concurrently 80 with the working movements of the slide-lock.

30. In a firearm of the class described, the combination with a frame having transversely thereof a shaft-seat, and with a slide 90 having a lock-face, of a cross-shaft in said shaft-seat, and a slide-lock having a hub-portion pivotally supported on the frame adjacent to said shaft-seat, and having a stop-face co-operative with said lock-face of 95 the slide, said shaft and said hub-portion having appurtenant to one of them an actuator-device coactively engaging the other of them, and arranged for turning the shaft concurrently 100 with the working movements of the slide-lock.

31. In a firearm of the class described, the combination with a frame having a shaft-seat, a barrel, and a slide having a lock-face, of a frame-and-barrel-uniting 105 cross-shaft in said shaft-seat; a slide-lock having a hub-portion journaled on the frame adjacent to said shaft-seat, and having a stop-face co-operative with said lock-face of the slide, said shaft and said hub-portion 110 having appurtenant to one of them an actuator-device coactively engaging the other of them, and arranged for turning the shaft concurrently with the working movements 115 of the slide-lock; and means appurtenant to the slide for retaining said shaft in said seat, and for releasing the shaft when the slide is in one position thereof on the frame.

32. In a firearm of the class described, the combination with a frame having a shaft-seat, a barrel, and a slide having a lock-face, of a frame-and-barrel-uniting cross-shaft in said shaft-seat; a slide-lock having a hub-portion journaled on the frame adjacent to said shaft-seat, and having a stop-face co-operative with said lock-face of the slide, said shaft and said hub-portion having 120 appurtenant to one of them an actuator-device coactively engaging the other of them, and arranged for turning the shaft 125 130

concurrently with the working movements of the slide-lock; means coactive with the barrel for transmitting a movement-resisting force through said shaft and actuating device to the slide-lock; and, means appurtenant to the slide and arranged for normally retaining said shaft in said seat and also for retaining the slide-lock on the frame, and also arranged for releasing the

shaft when the slide is in one position thereon the frame and for releasing the slide-lock when the slide is in another position on the frame. 10
